UNITED STATES PATENT OFFICE.

JOSEPH KROUPA, OF ST. LOUIS, MISSOURI.

GRATE.

SPECIFICATION forming part of Letters Patent No., 286,140, dated October 2, 1883.

Application filed May 25, 1883. (No model.)

To all whom it may concern:

Be it known that I, JOSEPH KROUPA, a citizen of the United States, residing at St. Louis, in the State of Missouri, have invented certain new and useful Improvements in Grates; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in grates and grate-bars; and it consists in the construction, combination, and arrangement of the several parts, as will be hereinafter more fully described and claimed.

In the drawings, Figure 1 is a plan and Fig. 2 is a side view of a grate constructed according to my invention. Fig. 3 is a detail perspective view of one of the grate-sections, and Fig. 4 is a detail view of the crank-shaft, all of which will be described; and Fig. 5 is a detached view, showing a slight modification.

The frame A is provided on its opposite ends with spindles A', which are intended to be supported in suitable bearings, so that the frame and the mechanism it carries may be rocked in the line of its length. In the side bars of this frame, near its ends, I provide bearings a a for the grate-sections, and about the middle of said bars I form the bearing a' for the crank-shaft. From the inner sides of the end bars of the frame A, I project the short breaking bars a², which are in the same plane with the side bars of the said frame A, and I also project the bars a² up over the space occupied by the cross-bars of the grate-sections. Small pieces a⁴ a⁴ are projected from the sides of the frame A in toward the rocking ends of the grate-sections.

The grate-sections B B are constructed exactly alike, and made preferably with three parallel bars, B' B² B', and the cross-bar B³. This cross-bar is extended on either side beyond the bars B', and its extended ends are rested in the bearings a, providing substantially a pivotal connection or support for the sections near the ends of the frame A. The bars B' B² are constructed with the project-

tions b' and b², arranged, respectively, at the rocking ends and about the middle portion of the said bars, to aid in the breaking and distribution of the coals and ashes as the sections are rocked in the manner hereinafter described. Through the bars B², about midway the ends thereof, I form the horizontal slot C, the upper side of which is in the same plane with the under side of the bars B' B', in line with the said slot. This may be accomplished by cutting away the under side of the bars B', or forming the slot C in a downwardly-extended portion of the bar B². Where so desired, the slot C could be made through more than one of the bars. The reason of such construction will appear hereinafter. When the sections B are placed in the frame A, it will be seen that the bars of their meeting or adjacent ends interlap. The slots C of the two sections coincide, and the bars in which said slots are formed are arranged next to each other.

The crank-shaft D is constructed with the spindle portions d d, which rest in the bearings a' in the frame A, and the angular portion d', to receive the key E, is extended from one of these spindles, as shown. Next to the spindles d, I form the stop portions d², which are preferably made in the flat form shown, with their edges d³ projected a short distance beyond the outer side of the spindles d, and its edge d⁴ is arranged in line with the rod d⁵, which rod forms a crank, the center of motion of which is the spindle d, as will be understood on reference to the drawings. On the inner end of the portion d' shoulders d⁶ are formed, which, together with the shoulders formed on the ends of the adjacent portions d⁷, ordinarily serve to retain the shaft in its bearing. Where so desired, collars or disks e may be provided at the opposite ends of the spindle or bearing d, next the angular portion d', as shown in Fig. 5, so as to prevent the falling of the pivot or spindle d from its place as the frame A is tilted, and retain the shaft D in position.

In setting up the grates the sections are arranged in the position shown in Fig. 1, with their bars interlapped with the bar B² of one section next the bar B² of the other, and the slots C through the said bars coincident. The shaft D is then passed through the slots C into

place, and the sections are bent on the said shaft as a hinge, so that their rods B^3 may be slipped into their bearings a , and the shaft D is dropped into its bearing a' , and the grate is 5 ready for use. The rod d^5 works in the bars B^2 , while the portion d^2 rests under and bears against the bars B' of the sections. As the shaft is rocked by the key E from side to side, it will be seen that, when the rod d^5 is brought 10 to the crown of the arc it describes, the sections will be raised, as indicated in dotted lines. When the rod d^5 is brought to the horizontal plane of the spindles d , the tendency of the 15 said sections, being pivoted in the bearings a , would be to fall below the plane or level of the frame A , but for the stop portion d^2 , the edge d^3 of which bears under the bars B' , and a counterbracing is had between the said edge d^3 , bearing up against the under side of the 20 bars B' of one section, and the rod d^5 , within the slot C of the bar B^2 of the same section, and the sections are prevented from falling below the level of the frame. For this purpose the portion d^2 need not be flat and 25 extended beyond the spindle, as shown, but might be made an extension of the spindle portion d . I prefer, however, to make it as shown, as there is thus provided the edge d^4 , which aids in the lifting action of the sections 30 bearing under the bars B' thereof, as has been described. I prefer to pivot both sections and operate them both by the crank-shaft; but where so desired one only of the sections may be pivoted at one end and supported by 35 the crank-shaft, as will be readily understood; but by pivoting both sections and operating them by the crank-shaft a better and more efficient shaking is obtained.

Having thus described my invention, what 40 I claim, and desire to secure by Letters Patent, is—

1. In a grate, the combination, substantially as set forth, of a grate-section pivotally sup-

ported at one end, and having one or more of its bars provided with a horizontal slot, and a 45 crank-shaft supporting the rocking end of the said section, and constructed with the rod d^5 and flat or stop portion d^2 , and suitably journaled, all as and for the purposes set forth.

2. In a grate, the combination, substantially 50 as hereinbefore set forth, of the grate-sections having their outer ends pivotally supported and meeting and interlapping at their adjacent ends, and a crank-shaft arranged under and providing a support for the meeting ends 55 of the grate-sections, and suitably journaled, whereby it may be revolved or rocked from side to side, as specified.

3. The combination of the frame having 60 spindles at its opposite ends, the grate-sections having one or more of their bars provided with a horizontal slot, and their other bars, on the under side thereof, in line with said slot, conformed to the plane of the upper side thereof, and the crank-shaft journaled in 65 the framing, and constructed with the rod d^5 and flat or stop portion or portions d^2 , the said parts d^5 d^2 being arranged to counterbrace and hold the section in a level position when at rest, substantially as specified.

4. The grate, substantially as described and shown, consisting of the frame A , having spindles A' A' , the sections B , pivoted at their outer ends and interlapping at their meeting ends, and provided in one or more of their 75 bars with slot C , and crank D , suitably journaled, and constructed with the rod d^5 and flat or stop portion d^2 , all arranged as and for the purposes specified.

In testimony whereof I affix my signature in 80 presence of two witnesses.

JOSEPH KROUPA.
